UNITED STATES PATENT OFFICE.

ROBERT H. GREENHALGH, OF SALT LAKE CITY, UTAH.

BRACE-BIT CHUCK.

1,256,475.

Specification of Letters Patent. Patented Feb. 12, 1918.

Application filed October 17, 1916. Serial No. 1,26,155.

To all whom it may concern:

Be it known that I, ROBERT H. GREENHALGH, a citizen of the United States, residing at Salt Lake City, in the county of 5 Salt Lake and State of Utah, have invented new and useful Improvements in Brace-Bit Chucks, of which the following is a specification.

The present invention contemplates the 10 production of a chuck, and more particularly a brace bit chuck.

The salient feature of the invention is the provision of a jaw so designed and associated with the chuck to positively hold the 15 bit within the chuck in such a manner as to prevent any accidental lateral movements of the bit and direct the latter in a perpendicular line through the timber during the boring action of such bit.

20 To this end, use is made of a jaw embodying spaced faces and so associated within the socket of the chuck to adapt the jaw for a lateral movement, thus upon the movement of the jaw from the socket of the 25 chuck permits of the bit tang being inserted or extracted from the socket of the jaw.

A still further object of the invention resides in the provision of a novel means for locking the jaw against movement with respect to the chuck head, thus upon the boring 30 operation of the bit the said locking means is held against movement and prevents the tang from having any loose movement in the jaw.

35 With the above and other objects in view, the invention consists in the novel features, details of construction and combination of parts which will hereinafter be more fully set forth, illustrated in the accompanying drawing and pointed out in the appended claims.

Figure 1 is a view in side elevation of an ordinary brace showing the jaw associated with the chuck head and in closed position, 45 the locking means for the jaw being illustrated in section;

Fig. 2 is a side elevation of a slight modified form of chuck head used in connection with boring machines, the locking means being illustrated in released position and with the jaw shown in a released position, the bit tang being illustrated as secured to said 50 jaw;

Fig. 3 is a section on line 3-3 of Fig. 1; 55 Fig. 4 is a rear elevation of the form of chuck head shown in Fig. 2 of the draw-

ing, the locking means shown in locked position, the jaw being illustrated in locked position and illustrating a slight modified form of locking means for the jaw when 60 the chuck head is used in connection with boring machines;

Fig. 5 is a further modified form showing the use of the chuck head for use on lathes or drill presses; 65

Fig. 6 is a further modified form showing the chuck head as an extension for the brace bits;

Fig. 7 is a detail perspective view of the locking means shown in Fig. 1 of the drawing; 70

Fig. 8 is a detail perspective view of the locking means shown in Figs. 2, 4, 5 and 6 of the drawing; and

Fig. 9 is a side elevation of a further 75 modified form of chuck showing the jaw as being slidably associated with the chuck instead of pivotally connected thereto.

In the accompanying drawing, reference being had more particularly to Fig. 1, A 80 denotes the U-shaped brace provided with a chuck 5 having its shank 6 securely fastened in the opening 7 formed terminally on the arm B of the brace.

The chuck in all forms of the invention, 85 with the exception of Fig. 9, is provided with a socket 8 having its walls 9 flared in a direction toward the lower end of the chuck and the base portion of the socket, designated by the reference character 10 is 90 of substantially rectangular form in cross section. The point of formation of the shank 6 with the chuck 5 presents a downwardly beveled shoulder 11, the purpose of which will be hereinafter more fully set 95 forth as the description of the invention is proceeded with. A pin 12 passes through the walls forming the rectangular base portion 10 of the socket, and through the rectangular shank 14 of the jaw 15 serving to 100 pivotally connect said jaw in the socket 9 of the chuck and adapting the same for a lateral swinging movement, better shown in Fig. 2 of the drawing. The said jaw 15 is of substantially wedge-shaped or tapering 105 formation, whereby when the jaw is in closed position, that is to say, when said jaw is swung between the walls of the socket 9, the same will snugly fit therebetween, and to an extent prevent any loose movement of 110 the jaw with respect to the chuck.

The character 16 denotes a locking mem-

ber for the jaw and used in connection with the brace bit chuck, as illustrated in Figs. 1 and 7 of the drawing, and this form of locking means embodies a hollow sleeve 17. 5 One of the walls of the material forming the sleeve is extended to provide a retainer 18. Provided on the outer surface of the upper inwardly beveled portion 19 of the retainer is a laterally extending manipulating portion 20. In use of the form of locking member above referred to, after the jaw 14 has been swung to a closed position, previous to which the recess 21 of the bit tang 22 is reposed on the toothed extremities 23 10 15 20 25 30 35 40 45 50 formed on the extremities of the spaced legs 24 of the jaw, upon the insertion of the bit tang within the socket 25 of the jaw, the jaw being thence closed and the locking member 16 is moved downwardly on the chuck to embrace the jaw, after which the beveled portion 19 of the retaining member co-acts with the beveled portion 11 of the chuck and is lodged under the arm B of the U-shaped brace A. Due to this manner of locking the retaining member on the chuck, the said retaining member will be positively prevented from moving lengthwise of the chuck upon the boring action of the bit.

The locking member 26 illustrated in Figs. 2, 4, 5, 6, 8 and 9 of the drawing is illustrated as embodying a hollow cylindrical sleeve provided at its upper end with an inwardly flattened beveled portion 27 adapted to repose on the beveled portion 11 of the chuck, and when this beveled portion 27 of the sleeve is brought into registration with the flattened portion 29 of the chuck head, the locking member will be partially rotated, and due to this operation, will lock the locking member on the chuck and prevent movement thereof longitudinally of said chuck. The upper extremity of the shank 14 of the jaw 15 is provided with an outwardly and downwardly beveled portion 25' adapted to engage with a similar beveled portion 26' formed on the base of the socket 9, to permit the swinging of the jaw 15 in an outward and lateral direction, and controlling the swinging of the jaw in only one direction with respect to the socket.

The modified form of invention illustrated in Fig. 9 of the drawing shows the base portion of the socket being of substantially circular form in cross section, and designated by the reference character 28, adapted to receive the substantially cylindrical bulged portion 29' formed on the free extremity

of the shank 14 of said jaw, thus slidably mounting the jaw in the socket 9 of the chuck for lateral sliding movement. 60

The shank 30 of the type of chuck illustrated in Fig. 5 of the drawing is provided with a drift slot 31 whereby a tool or other instrument may be inserted therein and serve to extract the chuck from a lathe or 65 drill press.

From the foregoing description, taken in connection with the accompanying drawing, the advantages of construction and the method of operation of the invention will be 70 readily apparent to those skilled in the art to which the invention relates, and while I have described the principles of operation of the invention, together with the device which I now consider to be the best embodiment thereof, I desire to have it understood that the device shown is merely illustrative, and that such changes may be made when desired as are within the scope of the claims 75 appended hereto. 80

Having thus described the invention, what is claimed is:

1. In combination with a chuck provided with a shank, the point of formation of the shank with the chuck presenting a beveled peripheral portion, a jaw associated with the chuck for receiving therein the bit tang, means for connecting the jaw with the chuck for lateral movement, a locking member for holding said jaw against movement, and means formed on the upper portion of said locking member and adapted to engage with the beveled peripheral portion of the chuck to prevent movement of said locking member during the turning action of the bit. 95

2. A device of the character set forth embodying a chuck provided with a tapering socket, a jaw of a configuration conforming with the socket of the chuck and mounted therein for lateral movement, said jaw comprising spaced legs formed with toothed extremities and the spacing of the legs forming the jaw with a socket adapted to receive the bit tang therein, the tang of the bit reposing upon the toothed extremities of the legs and preventing any accidental displacement of the bit from said jaw when the latter is in a closed position, and means for locking the said jaw against any accidental lateral movement with respect to said socket. 110

In testimony whereof I affix my signature.

ROBERT H. GREENHALGH.
